RAIL FASTENING

William S. Boyce, Denver, Colo., assignor to The Colorado Fuel and Iron Corporation, a corporation

Application May 18, 1940, Serial No. 335,879

15 Claims. (Cl. 238—349)

This invention relates to rail fastenings of the type which employs a resilient lock for holding the rail against its seat with a spring action and is concerned more particularly with a novel fastening of this type in which the spring lock is held in its operative position on a tie plate by its action on a self-locking retainer. The new fastening may be installed quickly and easily, requires little or no servicing, and may be manufactured at low cost.

This application is a continuation-in-part of my copending application Serial No. 293,174, filed September 2, 1939. In my copending application, I have disclosed a rail fastening including a resilient rail lock pivotally mounted in an opening in the tie plate, and a spike disposed in the same opening in engagement with the outer face of the lock and serving the dual function of holding the plate on the tie and maintaining the lock in a cramped position so that it exerts a spring action on the rail to urge the rail against its seat. In such a fastening, the spring lock normally exerts a reaction on the spike in the form of an outward thrust, and the lock is adapted to fulcrum on its pivotal mounting because of the spring reaction so as to take up automatically any looseness which might otherwise develop between the parts due to wear, corrosion, etc. It has been found in practice that rail fastenings of this construction prevent longitudinal movement of the rail, reduce lateral play and vertical movement of the rail due to passing rail loads, and eliminate much of the noise and vibration incident to such loads. Also, the fastening is easily installed and permits handling of the track in the same manner as with conventional fastenings, and its cost is comparable with that of present standard fastenings.

The proper functioning of this fastening, however, is dependent upon its correct installation and adequate maintenance. More particularly, unless the spikes adjacent the spring locks are driven carefully and uniformly, the locks will normally exert different pressures on the rail, which is objectionable. Also, when the track is faulty due, for example, to looseness of the ties on the bed, splitting or deterioration of the ties, or improper seating of the tie plates on the ties, there is a tendency for the spikes adjacent the locks to work out of the ties. This is so because each of these spikes is wedged in the plate by the spring lock with a greater force than the holding power of the tie so that when the plate moves upwardly from the tie under the action of passing rail loads, the spike tends to move with

the plate out of the tie instead of the plate moving along the spike. Additionally, there is a greater wedging of the spike in the plate during upward movement of the plate than during downward movement, and, accordingly, the plate may move downwardly along the spike but in its reverse movement it tends to grip the spike and draw it out of the tie.

The present invention, therefore, is directed to the provision of a novel rail fastening which does not require a high standard of track maintenance and which, in addition, provides a more uniform pressure between the spring and the rail. These advantages are obtained in the new fastening by reason of its inclusion of a novel retainer which is acted upon by the spring to lock the latter in its operative position without interfering with the pivotal action of the spring. According to the invention, the tie plate is formed on one side of the rail seat with an under-cut opening in which the spring lock is pivotally mounted. At its lower end, the lock is provided with a finger projecting inwardly into the undercut to prevent upward movement of the lock, and from the finger the lock extends upwardly out of the opening and then inwardly into contact with the rail base. The lock is adapted to fulcrum transversely of the rail on a part of the inner wall of the plate opening as a pivot and is held against the pivot by a retaining member wedged between the outer face of the lock and the outer wall of the opening. Because of the wedging action of the retainer and the pivotal mounting of the lock, the part of the lock overlying the rail base is urged downwardly against the rail so that the lock is distorted and not only exerts the desired spring action on the rail but also produces an outward reactive force on the retainer. Accordingly, the inter-engaging surfaces of the lock and retainer are maintained under considerable lateral pressure by the spring reaction of the lock, and accidental withdrawal of these parts is effectively prevented.

In the preferred construction, the retainer is formed with a head for limiting its downward movement into the plate, and the greatest thickness of the shank of the retainer is a substantial distance below the head. This increased thickness of the shank may be provided by a protrusion on the side of the shank remote from the spring lock and is such that the shank in the region of the protrusion will just fit between the lock and the outer wall of the plate opening when the lock is fulcrumed inwardly against the rail as far as possible. Thus, in the installation

of the fastening, the retainer can be driven home only when the lock is forced inwardly substantially the maximum distance, and when the retainer is in its final position, the reactive force of the lock tilts the retainer and the adjacent part of the lock outwardly on the protrusion as a pivot so that the thickened part of the shank forms in effect an expanded cotter key for preventing accidental withdrawal of the retainer. With this construction, the spring lock can be withdrawn only by removing the retainer, and the retainer can be removed only by forcing the spring lock back toward its fully distorted position.

It will be observed that the new fastening is of simple construction and is easily installed. The retainer cannot work loose during the life of the assembly, and the only maintenance service required is in connection with the usual spikes or lag screws for holding the tie plate on the tie. The pressure exerted by the lock springs on the rail is not affected by the driving of the spikes or the lag screws, and because of the retaining members a uniform spring action is provided along the rail even though the fastenings are installed by unskilled labor.

For a better understanding of the invention reference may be had to the accompanying drawings, in which

Fig. 1 is a sectional view of one form of the new fastening;

Fig. 2 is a plan view of the fastening shown in Fig. 1;

Figs. 3, 4 and 5 are sectional views of part of the fastening shown in Figs. 1 and 2, illustrating different steps of the installation, and

Fig. 6 is a sectional view of a part of a modified form of the fastening.

Referring to Figs. 1 and 2, the fastening there shown comprises a tie plate 10 mounted on a tie 11 and provided on the bottom with spaced transverse ribs 12 embedded in the tie to resist longitudinal movement of the plate. Preferably, the bottom of the plate is formed with spaced longitudinal recesses 13 to prevent shifting of the plate transversely on the tie, as described in United States Letters Patent No. 2,018,658 of William S. Boyce. On the top of the plate is a canted rail seat 14 on which a rail 15 is mounted between a pair of abutment shoulders 16 adjacent the edges of the rail base.

The tie plate is formed on one side of the rail seat with an opening 18 which, as shown, is rectangular and receives a spring lock 19 for urging the rail against the seat. The lock may be made of a heavy strip of spring metal and is formed at its lower end with a finger 20 projecting inwardly into an undercut portion 21 of the opening. The lock is adapted to fulcrum transversely of the rail on the corner 22 at the outer edge of the under-cut portion as a pivot. From the pivot 22, the lock extends upwardly through the opening and then curves inwardly over the rail base where it is provided with a reversely turned portion 23 engaging the top of the rail base.

The lock is wedged in the plate opening by a retainer 24 which, as shown, is in the form of a headed member having a shank provided with a protrusion 25 a substantial distance below the head. Preferably, the inner face 26 of the shank is flat and fits closely against the outer face of the lock, while the outer face of the shank diverges downwardly to the protrusion 25 and then curves inwardly to the lower end of the retainer. The part of the retainer directly below the head

may be backed by an abutment 27 which is integral with the plate and is preferably formed in accordance with the method described in an application of Marvin L. Cantrell and Oscar A. 5 Hed, Serial No. 295,204 filed September 16, 1939. The abutment 27 extends transversely of the tie plate and is joined at its ends with similar abutments 27' extending lengthwise of the plate along the sides of the opening 18.

Because of the wedging action of the retainer 24, the spring lock 19 is biased on the pivot 22 in a counter-clockwise direction, as seen in Fig. 1, with the result that the reversely turned portion 23 is urged downwardly against the top of the rail base and the lock is distorted. This distortion of the lock produces a reactive force which exerts itself in an outward thrust against the retainer 24 above the level of the protrusion 25, whereby the retainer is tilted outwardly against the adjacent wall of the plate opening on the protrusion as a pivot. Thus, the inter-engaging surfaces of the retainer and the lock are inclined to the vertical so that the shank of the retainer in the region of the protrusion 25 forms in effect an expanded cotter key which positively locks the retainer in the plate opening. The downward thrust of the lock against the top of the rail base serves to retard the vertical movement of the rail incident to passing train loads, dampens vibration, and opposes longitudinal movement of the rail on the plates due to traffic conditions or to thermal expansion of the rail itself. By reason of the lateral reactive force of the lock on the retainer, any looseness which might otherwise develop between the parts in the plate opening and the walls of the opening due to wear and corrosion is automatically taken up by movement of the lock in a clockwise direction on the pivot 22.

The tie plate 10 may be secured to the tie in any suitable manner, as, for example, by means of spikes 30 driven through the plate adjacent the rail base. The heads of the spikes, as shown, engage the rail base and supplement the action of the lock in holding the rail against its seat. If desired, a lock 19a similar to the lock 19 may be arranged on the opposite side of the rail seat to increase the spring action on the rail, and additional spikes 31 may be driven through the plate a substantial distance outwardly from the spikes 30 to supplement the latter.

In the installation of the new rail fastening, the clip 19 is inserted in the opening 18 with the finger 20 extending into the under-cut portion of the opening. In the initial position of the lock, the end of the reversely turned portion 23 engages the top of the rail base and holds the main body of the lock in an outward position so that the part extending upwardly through the opening is inclined to the vertical at an angle A, as shown in Fig. 3. To insert the retainer 24, it is necessary to force the lock counter-clockwise on its pivot 22, as by means of a suitable tool, so that the part of the lock extending through the opening is substantially vertical, as shown in Fig. 4. In this fully distorted position of the lock, the thickened portion 25 of the retainer will just fit between the outer face of the lock and the outer wall of the opening. In inserting the retainer, its inner face 26 is placed against the outer face of the lock, and then the retainer is moved downwardly into the plate opening until the head engages the top of the abutment 27. When the spring lock is released by the tool

which deflected it, the reactive force produced

by distortion of the part 23 tilts the retainer and the adjacent part of the lock outwardly through an angle B, as shown in Fig. 5, until the outer face of the retainer shank above the thickened portion 25 lies flat against the outer wall of the plate opening. In this position of the lock, the angle B between the vertical and the part of the lock projecting through the opening is considerably smaller than the angle A shown in Fig. 3. Thus, while the lock in its final position is not fully distorted, it is distorted a substantial amount so that it normally exerts on the rail a downward force of considerable magnitude.

Since the opposed abutments 27 join the projection 21 to the rail abutting shoulder 16, they serve to brace or reinforce this projection which is subjected to a constant pressure from the retainer under the action of the spring lock. Moreover, the abutments 27' increase the strength of the plate and with the projection 21 and shoulder 16 form a housing for the rail lock and retainer located above the surface of the tie plate, thereby reducing the penetration to these members of corrosive or other destructive elements tending to weaken the structure. The lock 19 in resisting longitudinal movement of the rail is subjected to torsional stresses tending to impair the contact relation between the lock and retainer, and the abutments 27 and 27', in addition, serve to hold these members securely in their proper relation. Since the top surfaces of the abutments 27 and 27' are coplanar with the top of the rail abutting shoulder 16, the removal of any burrs formed around the periphery of the opening incident to the punching of the plate is facilitated, thereby reducing the cost of the plate.

The modified form of the fastening shown in Fig. 6 is similar to that illustrated in Figs. 1 and 2, except that a different form of retainer is employed. As shown in Fig. 6, the retainer 33 is provided with a head engaging the top of the abutment 27, and a shank extending downwardly from the head into the opening 18. The inner face of the shank near the bottom is provided with an inwardly extending lug 34 which engages the lower inclined surface of the finger 29 on the spring lock, and the front face of the lock curves inwardly toward the lug 34. In installing the retainer, the lock 19 is forced counter-clockwise on its pivot until the part projecting through the plate opening is substantially vertical. The retainer may then move down into the opening from the dotted line position shown in Fig. 6, and when the retainer is in its lowermost position, the reactive force of the lock tilts it clockwise to the position shown in full lines wherein the lug 34 is under the finger 20 on the lock and prevents removal of the retainer.

It will be apparent that in both forms of the fastening illustrated, the retainer can be withdrawn from the plate opening only by forcing the spring lock inwardly on its pivot until the part of the lock adjacent the retainer is substantially vertical, and the lock can be withdrawn only after removing the retainer. The force required to deflect the lock preparatory to removing the retainer is considerable and may be as much as from 2,000 to 4,000 pounds, depending on the strength of the lock and the proportioning of the parts. Accordingly, in the use of the fastening, it is impossible for the retainer or the lock to work out of the opening in the absence of actual breakage. By making the retainers of

standard size, the wedging of the lock and therefore the spring pressure on the rail will be uniform regardless of irregularities in the seating of the tie plates or in the driving of the spikes. While I have described the installation of the fastening by the use of a tool for forcing the lock to its fully distorted position, it will be understood that the installation may be effected without the tool by inserting the end of the retainer in the space between the lock and the outer wall of the opening and then driving the retainer home. During the driving operation, the curved outer face of the retainer near the bottom of the shank acts as a cam on the adjacent wall of the opening and forces the lock to its fully distorted position. When the thickened portion of the shank enters the opening (Fig. 4), it is impossible for the lock to pivot outwardly until the thickened portion moves below the line of the resultant reactive force of the lock against the retainer.

In the rail fastenings illustrated, the outer wall of the plate opening and the inner, lock-engaging face of the retainer are not parallel but converge upwardly. If desired, these surfaces may be parallel to facilitate insertion or withdrawal of the retainer, in which case the shank of the retainer may be of uniform thickness and is held in position by the frictional resistance between the retainer and the lock and between the retainer and the outer wall of the opening. This frictional resistance is of considerable magnitude due to the lateral reactive force of the lock on the retainer. However, the fastenings shown in the drawings are preferred because with the slight degree of angularity between the inner and outer faces of the retainer the frictional resistance is augmented by the cotter key action of the protruding part of the retainer shank. While the plate opening 18 is shown as rectangular, it may be of any other desired shape. For example, it may be T-shaped as shown in my copending application Serial No. 293,174, in which case the retainer may be considerably narrower than the lock so that it will fit in the stem of the opening.

I claim:

1. In combination, a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is pivotable transversely of the rail, and a retainer disposed wholly above the bottom of the plate and wedged in the opening between the outer face of the lock and the outer wall of the opening to bias the lock inwardly on its pivot and thereby urge the flexible part against the rail base and distort said part, the retainer having a part in the opening increasing in thickness toward its lower end and the lock exerting a lateral reactive force on the retainer to urge the same against the outer face of said opening and thereby secure the retainer against accidental removal from the opening.
2. In combination, a tie plate having a rail seat and an opening on one side of the seat, a rail mounted on the seat, a spring lock in the opening including a laterally extending finger underlying part of the plate for resisting upward

movement of the lock, the lock also including a flexible part extending inwardly over the rail base into engagement with the top of the base, the plate having a pivotal mounting for the lock in said opening on which the lock is pivotable transversely of the rail, and a retainer wedged in the opening between the outer face of the lock and the outer wall of the opening to bias the lock inwardly on its pivot and thereby urge the flexible part against the rail base and distort said part, the retainer having a part in the opening increasing in thickness toward its lower end and the interengaging faces of the retainer and the lock being inclined upwardly and outwardly from the rail under the reactive force of the lock on the retainer to secure the retainer against accidental removal from the opening.

3. In combination, a tie plate having a rail seat and an undercut opening on one side of the seat, a rail mounted on the seat, a spring lock in the opening including a laterally extending finger projecting into the undercut for resisting upward movement of the lock, the lock also including a flexible part extending inwardly over the rail base into engagement with the top of the base, the plate having a pivotal mounting for the lock in said opening on which the lock is pivotable transversely of the rail, and a retainer wedged in the opening between the outer face of the lock and the outer wall of the opening to bias the lock inwardly on its pivot and thereby urge the flexible part against the rail base and distort said part, the retainer having a part in the opening increasing in thickness toward its lower end and the lock exerting a lateral reactive force on the retainer tending to tilt the interengaging faces of the retainer and the lock outwardly and secure the retainer against accidental removal from the opening.

4. In combination, a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is pivotable transversely of the rail, and a retainer wedged in the opening between the outer face of the lock and the outer wall of the opening to bias the lock inwardly on its pivot and thereby urge the flexible part against the rail base and distort said part, the retainer having a part in the opening increasing in thickness toward its lower end and the lock exerting a lateral reactive force on the retainer tending to tilt the interengaging surfaces of the retainer and the lock outwardly whereby said interengaging surfaces and the outer wall of the opening converge upwardly and prevent accidental removal of the retainer from the opening.

5. In combination, a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is movable transversely of the rail, and a retainer wedged in the opening between the outer

outer face of the lock and the outer wall of the opening to bias the lock inwardly on its pivot and thereby urge the flexible part against the rail base and distort said part, the retainer including a shank portion having its greatest thickness below the line of the resultant reactive force of the lock on the retainer, and the retainer being tilted outwardly on its thickened portion under said reactive force whereby the interengaging surfaces of the retainer and lock and the outer face of the opening converge upwardly and prevent accidental removal of the retainer from the opening.

6. In combination a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is movable transversely of the rail, and a retainer wedged in the opening between the outer face of the lock and the outer wall of the opening to bias the lock inwardly on its pivot and thereby urge the flexible part against the rail base and distort said part, the retainer including a shank portion having its greatest thickness below the line of the resultant reactive force of the lock on the retainer and also including a head on the shank for limiting the downward movement of the retainer in said opening, the retainer being tilted outwardly on its thickened portion under said reactive force whereby the interengaging surfaces of the retainer and lock and the outer face of the opening converge upwardly and prevent accidental removal of the retainer from the opening.

7. In combination, a tie plate having a rail seat, an opening on one side of the seat, and a raised abutment along the outer edge of the opening, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is movable transversely of the rail, and a retainer wedged in the opening between the outer face of the lock and the outer wall of the opening to bias the lock inwardly on its pivot and thereby urge the flexible part against the rail base and distort said part, the retainer including a shank portion backed by said abutment and having its greatest thickness below the line of the resultant reactive force of the lock on the retainer, the retainer also including a head on the shank engaging the top of said abutment for limiting the downward movement of the retainer in the opening, the retainer being tilted outwardly on the thickened portion under said reactive force whereby the interengaging surfaces of the retainer and lock and the outer face of the opening converge upwardly and prevent accidental removal of the retainer from the opening.

8. In combination, a tie plate having a rail seat and an undercut opening on one side of the seat, a rail mounted on the seat, a spring lock in the opening including a laterally extending finger projecting into the undercut for resisting

upward movement of the lock, the lock also including a flexible part extending inwardly over the rail base into engagement with the outer edge of the undercut portion forming a pivot for the lock on which the lock is pivotable transversely of the rail, the lock and the adjacent wall of the opening diverging upwardly from the pivot, and a retainer wedged in the opening between the outer face of the lock and the outer wall of the plate opening to bias the lock inwardly on the pivot and thereby urge the flexible part against the rail base and distort said part, the retainer having a part in the opening increasing in thickness toward its lower end and the lock exerting a lateral reactive force on the retainer to secure the retainer from accidental removal from the opening and being movable inwardly on its pivot against the spring action of said flexible part to release the retainer.

9. For use in a rail fastening including a tie plate having a rail seat and an opening on one side of the seat, a rail on the seat, and a spring lock in the opening engaging the rail base, a retainer insertible in the opening to wedge the lock against the rail base and including a shank having a substantially flat face engageable with the lock, the opposite face being engageable with the outer wall of the plate opening and diverging downwardly from the plane of said first face, and a head on the shank projecting outwardly from said diverging face.

10. In combination, a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is movable transversely of the rail, and a retainer wedging the opening between the outer face of the lock and the outer wall of the opening to bias the lock inwardly on its pivot and thereby urge the flexible part against the rail base and distort said part, the retainer including a shank portion having a lug on the inner face thereof projecting inwardly under the lock, the lock exerting a lateral reactive force on the retainer to tilt the retainer outwardly and prevent accidental removal of the retainer from the opening.

11. For use in a rail fastening including a tie plate having a rail seat and an opening on one side of the seat, a rail on the seat, and a spring lock in the opening engaging the rail base and having means underlying a portion of the tie plate, a retainer insertible in the opening to wedge the lock against the rail base and including a shank having a substantially flat face engageable with the lock and a convex, rounded face engageable with the outer wall of the plate opening, a head on the shank projecting outwardly from the convex face, and a lug on the flat face projecting outwardly from the plane thereof and adapted to underlie part of the lock.

12. In combination, a tie plate having a rail seat and an opening on one side of the seat, a rail mounted on the seat, a spring lock in the opening including a laterally extending finger underlying part of the plate for resisting upward movement of the lock, the lock also in-

cluding a flexible part extending inwardly over the rail base into engagement with the top of the base, the plate having a pivotal mounting for the lock in said opening on which the lock is movable transversely of the rail, and a retainer wedged in the opening between the outer face of the lock and the outer wall of the opening and having a pivotal mounting against said outer wall, the retainer having a part in the opening increasing in thickness toward its lower end and biasing the lock inwardly on the pivotal mounting for the lock to urge the flexible part against the rail base and distort said part, the lock exerting a lateral reactive force on the retainer tending to tilt the same on said pivotal mounting for the retainer whereby the interengaging faces of the retainer and the lock are inclined upwardly and outwardly from the rail to secure the retainer against accidental removal from the opening.

13. In combination, a tie plate having a rail seat and an opening on one side of the seat, a rail mounted on the seat, a spring lock in the opening including a laterally extending finger underlying part of the plate for resisting upward movement of the lock, the lock also including a flexible part extending inwardly over the rail base into engagement with the top of the base, the plate having a pivotal mounting for the lock in said opening on which the lock is movable transversely of the rail, and a retainer wedged in the opening between the outer face of the lock and the outer wall of the opening and having a pivotal mounting against said outer wall, the retainer having a part in the opening increasing in thickness toward its lower end and biasing the lock inwardly on the pivotal mounting for the lock to urge the flexible part against the rail base and distort said part, the lock exerting a lateral reactive force on the retainer tending to tilt the same on said pivotal mounting for the retainer whereby the interengaging faces of the retainer and the lock are inclined upwardly and outwardly from the rail to secure the retainer against accidental removal from the opening, said second pivotal mounting being disposed below the resultant reactive force of the lock on the retainer.

14. In combination, a tie plate having a rail seat and an opening on one side of the seat, a rail mounted on the seat, a spring lock in the opening including a laterally extending finger underlying part of the plate for resisting upward movement of the lock, the plate also including a flexible part extending inwardly over the rail base into engagement with the top of the base, the plate having a pivotal mounting for the lock in said opening on which the lock is movable transversely of the rail, a retainer wedged in the opening between the outer face of the lock and the outer wall of the opening and having a pivotal mounting against said outer wall, the retainer biasing the lock inwardly on the pivotal mounting for the lock to urge the flexible part against the rail base and distort said part, an upwardly extending projection on the tie plate on the side of the retainer opposite the lock and engaging the retainer near the top thereof, the retainer having a part in the opening increasing in thickness toward its lower end and the lock exerting a lateral reactive force on the retainer tending to tilt the same on its pivotal mounting against said projection whereby the interengaging faces of the retainer

and the lock are inclined upwardly and outwardly from the rail to secure the retainer against accidental removal from the opening, and abutments on the top of the plate integral with said projection and extending inwardly therefrom on opposite sides of the retainer to reinforce the projection and maintain the lock and retainer in operative relation.

15. In combination, a tie plate having a rail seat and an opening on one side of the seat, a rail mounted on the seat, a spring lock in the opening including a part underlying a portion of the plate for resisting upward movement of the lock, the lock also including a flexible part extending inwardly over the rail base into en-

gagement with the top of the base, the plate having a pivotal mounting for the lock on which the lock is pivotable transversely of the rail, and a retainer wedged in the opening between the outer face of the lock and the outer wall of the opening to bias the lock inwardly on its pivotal mounting and thereby urge the flexible part against the rail base and distort said part, the retainer being tilted outwardly under the reactive force of the spring lock and having means operable in the tilted position of the retainer to secure the retainer against accidental removal from the opening.

WILLIAM S. BOYCE.
